APPARATUS FOR CLEANING ELECTRIC
LAMP BULBS

Ralph B. Thomas, Beverly, Mass., assignor to
Hygrade Sylvania Corporation, Salem, Mass., a
corporation of Massachusetts

Application January 22, 1941, Serial No. 375,427

1 Claim. (Cl. 15—7)

This invention relates to electric lamps and more particularly to electric lamp bulbs used in the manufacture of fluorescent lamps.

An object of this invention is to provide a means for cleaning the bulbs used in the manufacture of fluorescent lamps.

Another object is to provide a means for salvaging the powder from bulbs which have been imperfectly coated with a luminescent material.

Other objects, advantages and features will be apparent from the following specification taken in conjunction with the accompanying drawings in which:

Figure 1 is a side elevational view of the bulb cleaning mechanism;

Figure 2 is a detail, shown partly in section of the air escape bushing and the brush coupling;

Figure 3 is a perspective of the bulb carriage assembly;

Figure 4 is a side elevational view of a bulb in the process of being cleaned.

Similar reference characters refer to similar parts in the several views of the drawings.

In the manufacture of fluorescent lamps it is extremely important that the inner walls of the bulb be perfectly clear of impurities such as dust particles. Otherwise, the fluorescent coating will not be the smooth even coating which is desired. Thus one of the purposes of my invention is to obtain a perfectly clean bulb before the luminescent coating is applied.

Many times, in the processing of the lamp, for one reason or another, the coating is spoiled. It is then desirable to salvage the powder from the bulb. If this is done without contaminating it, the powder may be used over again. Thus another purpose of my invention is to provide a simple yet adequate means for salvaging the powder from the bulb.

In Figure 1, the tracks 1 are mounted on the channel 2. This channel may be mounted on a table or some other suitable support to hold it in a stationary position. The carriage bodies 3, 4, and 5 are mounted on the carriage axles 6 which in turn carry the carriage wheels 7. The bulb guides 8 and 9 are mounted on top of the carriage bodies 4 and 5, respectively.

The carriage body 3 has the shaft guide 10 mounted on the top thereof. As is more clearly brought out in Figure 3, it is through the bearings 11 that the shaft guide 10 with the carriage body 3 and the entire carriage assembly moves backward and forward to cause the bulb resting on the carriage guides 4 and 5 to envelop the rotating brush 15. This brush 15 which cleans

the bulbs extends from the brush coupling 14 which projects from the forward extremity of the shaft 13 enclosed within the shaft tube 12. The rearward extension of the shaft tube 12 extends back through the shaft tube supports 16 to the coupling 17. It is here that the shaft tube 12 ends and the shaft 13 is joined to the solid shaft 18 which is driven through the pulley 19 and the belt 20 mounted on the supports 21. Air may be introduced through the air line 22 in the shaft tube 12.

As shown in Figure 2, the air escape bushing 23 is located on the end of the driven shaft 13 and is enclosed by the shaft tube 12 except that at its forward end it permits the passage therethrough of air coming through the shaft tube 12 from air line 22 as shown in Figure 1. The brush coupling 14 extends from the bushing 23 and has attached at the forward end thereof the brush 15 shown in Figure 1.

Figure 1 also shows the connecting rod 24 running between the carriage body 3 on which the shaft guide 10 is mounted and the carriage body 4 on which the bulb guide 8 is mounted. Attached to the rear of the carriage body 3 is the rear bumper 25, shown in Figure 3, which, when the whole carriage assembly is moved in a rearward direction, will strike against the rear bumper spring 26 thus cushioning the carriage from the shaft tube supports 16. The connecting rod 24 is fixed to the carriage body 3 but freely fitted through the carriage body 4, as shown in Figure 3. Thus any shock transmitted through the connecting rod 24 as a result of the rear bumper 25 striking the rear bumper spring 26 will be absorbed through the two springs 28 held on the rod 24 through the collars 29, one in front and one in the rear of the carriage body.

40. In Figure 1, the forward movement of the carriage assembly is limited by the stop 30. Any shock resulting from the carriage assembly striking the stop 30 will be absorbed by the spring 31 on the stud 32 freely fitted through the carriage body 5.

Although, as seen in Figure 3, I have shown but two carriage bodies 4 and 5 with the bulb guides 8 and 9, respectively, mounted thereon, more than two may be used depending on the length of the bulb to be cleaned. It is apparent that if long bulbs were to be cleaned, either a greater spacing between carriage bodies or more carriage bodies along with an adjusted location of the shaft guide would be necessary. My apparatus is so constructed that such adjustments

may be very readily made without departing from the spirit of my invention.

When a bulb is to be cleaned, it is placed in the saddle of the bulb guides 8 and 9. A slight downward and rearward pressure is placed on the bulb thus causing the bulb carriage assembly to move along the tracks 1 and bring the bulb towards the brush 15. The bulb carriage assembly is moved along the tracks 1 far enough to cause the bulb to be cleaned its entire length by the rotating brush 15. The air coming from the air line 22 through the shaft tube 12 and out the air escape bushing 23 will, in conjunction with the rotating brush, remove all dust and other impurities from the inner walls of the bulb. This dust may be collected by some suitable means.

Figure 4 shows a means by which such materials as are removed from the walls of the bulb may be collected. It is extremely desirable to be able to salvage the luminescent powder from a defective lamp. Thus if the apparatus described above is connected to a vacuum and some suit-

able container this result may be achieved. Figure 4 shows the bulb 33 with the luminescent powder 23 on the inner walls thereof being cleaned by the rotating brush 15. When the bulb to be cleaned is placed on the bulb carriage, one end thereof may be connected to a vacuum line such as 35, as shown in Figure 4. By connecting this line to a vacuum pump and some suitable trap the luminescent coating may be readily and adequately salvaged.

What I claim is:

Apparatus for cleaning elongated tubular glass bulbs comprising: an axially fixed rotatable shaft; a shaft tube enclosing said shaft; an air inlet at the rearward extremity of said shaft tube; an air escape bushing at the forward extremity of said shaft tube; a rotating brush attached to said air escape bushing; a bulb carriage; and a track along which said bulb carriage may be moved to bring the bulbs into cleaning relation with said brush.

RALPH B. THOMAS.
